UNITED STATES PATENT OFFICE

JOHN KRASNODMSKY, OF MILWAUKEE, WISCONSIN, ASSIGNOR OF FIFTEEN PER CENT TO
ANTON J. KOSS, OF MILWAUKEE, WISCONSIN

AEROPLANE PROPELLER

Application filed January 1, 1931. Serial No. 505,993.

This invention relates to improvements in propellers and more particularly to propellers especially adapted for use for the propulsion of aeroplanes, and the like.

5 One of the objects of the present invention is the provision of an improved type of propeller of the multiple blade type wherein the blades are arranged one beneath the other in slightly offset position to increase the pulling power of the propeller when operating at a high rate of speed.

Another object of the present invention is the provision of a propeller of the multiple blade type, wherein the blades are integrally connected and arranged one beyond the other in slightly offset relation, with the blades arranged in sets, and the pitch of each blade of each set corresponding so that the blades will cooperate with each other in the propulsion of the machine, and thus increase the power derived from such a type.

A further object of the present invention is the provision of a propeller of the multiple blade type wherein blades are integrally connected one with the other and detachably mounted upon the main hub of the driving shaft, so that any unit of the propeller can be removed or replaced at the will of the operator.

30 With the above and other objects in view, the invention consists in the novel features of construction, the combination and arrangement of parts hereinafter more fully set forth, pointed out in the claims and shown in the accompanying drawing wherein:

Figure 1 is a front elevation of a propeller constructed in accordance with my invention;

40 Figure 2 is a sectional view on the line 2—2 of Figure 1;

Figure 3 is a detailed section on the line 3—3 of Figure 2; and,

45 Figure 4 is a perspective view of one unit illustrating a slightly modified form of the invention.

Referring more particularly to the drawing, it will be noted that a portion of the drive shaft 1 of an aeroplane is illustrated in the drawing as provided with an outer reduced threaded end. Mounted on the drive

shaft 1 is the hub 3 of the propeller which is retained in position upon the shaft by means of a removable nut 4.

Extending radially from the hub 3 and arranged in equal spaced relation are the integrally threaded sleeves 5 having annular collars 6 at the outer ends thereof and provided with annular shoulders 7 adjacent the hub portion 3.

As shown in Figures 1 to 3 inclusive, each unit of the propeller includes three blade members comprising the outer blades 8 and the central blade 9. It will be noted from the showing in Figure 2, that the pitch of each blade of this unit is uniform so that all of the blades of each unit will cooperate. The three blades of each unit are integrally connected by means of the transverse webs 10 and the central blade member 9 is provided with a threaded stem 11 adapted to engage the threads of the sleeve 5.

Each one of the blades 9 is provided with an annular shoulder 12 for engaging each one of the sleeves 5 at their outer ends. It will be noted that one of the blades 8 is somewhat longer than the other, and the inner ends of each blade are provided with spaced openings to receive the ends of the U-bolts 13 and 14.

As shown in Figure 2, the U-bolts 13 and 14 are fitted over the sleeve 5 from opposite directions and the ends of these bolts are passed through the spaced apertures in the ends of the two outside blades 8, and the bolts can be arranged along side of one another as the end of one blade 8 projects beyond the end of the other blade 8. Spacing blocks 13' and 14' are positioned between the two outside blades and the sleeve 5 with the ends of the bolts 13 and 14 passing through suitable apertures in these blocks. These blocks provide means whereby the two outside blades 8 are maintained in equal spaced relation through their lengths with the intermediate blade 9.

It will be apparent from the foregoing that I have provided a simple and comparatively inexpensive propeller of the multiple blade type which can be quickly attached to a hub on the driving axle of an aeroplane and wherein the several blades of each unit of the

propeller cooperate to increase the propulsion of the same.

In Figure 4, I have illustrated a slightly modified form of the invention wherein each unit is provided with a pair of blades, the blade 9' being provided with the threaded stem 11' and the blade 8' being provided with spaced apertures 15 whereby the blade 8' can be clamped onto one of the sleeves 5 by means 10 of a U-bolt, or the like.

In this form of the invention, the blades 8' and 9' are integrally connected by means of the webs 10' and the pitch of both blades is the same so that they will cooperate with 15 one another.

It will be apparent that each unit of the propeller can be made up of a plurality of blades with each blade cooperating so that the unit operates as a single blade, but the 20 unit is strengthened due to the number of blades used and the integral connection of the blades.

While I have shown and described the preferred embodiment of my invention, it will 25 be apparent from the foregoing that slight changes may be made in the construction when putting the invention into practice without departing from the spirit of the same or the scope of the appended claims.

30 I claim:

1. A propeller including a hub having radially projecting integrally threaded sleeves, and a plurality of multiple blade units each carrying a threaded stem for detachable engagement with said sleeves.
2. A propeller comprising a hub, a plurality of individual blade units secured to and radiating from said hub, each of said blade units including a plurality of equally distantly spaced blade sections of the same pitch and chord, with one arranged slightly in advance of the other.
3. A propeller comprising a hub having radially projecting integrally threaded sleeves, and a plurality of individual blade units each including a plurality of equally distantly spaced blade sections of the same pitch and chord, with one arranged slightly in advance of the other, a threaded stem carried by one of the blade sections for detachable engagement with a sleeve, a shank extension on the other blade sections disposed exteriorly of and in close proximity to a sleeve, and a U-bolt removably extending through 50 the shank extension and detachably engaging the sleeve.

In testimony that I claim the foregoing I have hereunto set my hand at Milwaukee, in the county of Milwaukee and State of Wisconsin,

JOHN KRASNODMSKY.
